UNITED STATES PATENT OFFICE.

LEE SCHOFIELD, OF LYTHAM, ENGLAND, ASSIGNOR OF ONE-HALF TO JAMES STOTT,
OF OLDHAM, ENGLAND.

GAS-HEATED WASHBOILER, BOILING-PAN, AND THE LIKE.

1,181,038.

Specification of Letters Patent. Patented Apr. 25, 1916.

Application filed September 4, 1913. Serial No. 788,124.

To all whom it may concern:

Be it known that I, LEE SCHOFIELD, a subject of the King of Great Britain, residing at Lytham, Lancashire, England, have invented certain new and useful Improvements in Gas-Heated Washboilers, Boiling-Pans, and the like, of which the following is a specification.

My invention relates to that class of boiler or water heater in which a float is employed for determining the degree of flame forming the heating medium. In such apparatus either the float is immersed in the liquid contained within the boiler or such float formed the cover with its wall dipping into an annular vessel surrounding the upper part of the apparatus, which vessel was completely isolated from the boiler. In either case the float was directly connected by suitable appliances to the burner and the rising and falling of the float determined the degree of flame issuing from the burner and so regulated the heat to the boiler, the connection between the burner and the float being such that the float could not be moved without in some way actuating the burner and further the apparatus was inadmissible as a washing boiler because in one instance the float was in the way and in the other the boiler was not contained within the float but was at a lower level the chamber positioned within the float constituting a steam chamber in which the material was steamed only and further the material could not be inspected because of the construction of the float unless it was removed and the float could not be easily removed because of the suction of the steam within the chamber holding the float tightly.

Now the object of my invention is to construct such a boiler or boiling pan or the like for use with gas stoves or gas burners in such a manner that the float is free and the lever or appliances connected with the gas valve and which is or are operated by the float can be moved free of the float if desired, and to provide a lid to the float or boiler so that the contents of the boiler can be easily examined during the boiling operations.

Figure 1 is a transverse vertical section of an apparatus embodying the features of the invention. Fig. 2 is a similar view showing a modification of the invention. Fig. 3 is a similar view showing a further

modification of the invention. Fig. 4 is an elevation of a portion of a heating apparatus showing the boiler or receptacle in section and the features of the invention applied thereto. Fig. 5 is a detail view of a still further modification relating to means for operating the float when the cover is open.

The wash boiler or pan *a* is inserted in a metallic or other ring *b*, see Fig. 1, to form with the boiler or pan a deep annular space *c*. The cover *d* of the boiler or pan is provided with a deep flange *e* from or near the outer edge and which is inserted in said space *c*, to provide a bell or float which rises and falls in the said annular space *c*. The object in constructing the annular space is to provide means for keeping the float or bell clear of the contents of the boiler or pan and thus prevent any interference with the float's movements. At the top of or over the float or bell thus formed is provided an attachment or lever *f* loosely resting thereon for operating a valve *h* on the gas service pipe to regulate the supply of fuel or gas supply after the manner of an ordinary gas valve directly the water or liquid boils sufficiently to raise the float or bell by its own vapor expansion properties. The cover *d* is provided with a hinged lid *d'* which forms part of the cover and a suitable type of catch may be fitted to the float or bell to keep it air tight when the lid is closed.

It may be that instead of employing a hinged lid on the float or bell of the boiler, a lid working in a suitable lateral slide could be used with greater convenience.

As an alternative to a float or bell covering practically the whole of the pan portion of the boiler, a comparatively small float or bell *d*, *e*, is used in conjunction with a comparatively small chamber *i* for securing freedom of action and isolation from the clothes as shown by Fig. 2. This chamber *i* may be in the nature of an open ended tube *j* having solid or perforated walls and effectively supported from the top of the boiler *a*, while the other end is positioned upon or almost upon the bottom of the pan or it may be formed of a curved piece of metal soldered or attached permanently to the wall of the pan *a* or it may be just loosely supported from the top as shown by Fig. 3, the wall of the pan forming the remaining portion of the chamber.

Although the lever *f* is suggested for conveying the float movements to the valve *h* it may be dispensed with by supporting the valve *h* directly over or above the bell or float *d, e*, as shown by Fig. 3.

It is preferred to use lever *f* with a loose end resting upon the float since by merely raising or moving the lever sidewise the float can be removed and cleaned if found necessary, as for instance, where the water is "hard."

The small hole or opening may be put in the crown of the float for relieving the slight expansion taking place before the water reaches 212 degrees Fah. but this does not give sufficiently quick relief when the boiler is being filled with water. During this operation the air underneath the float becomes slightly compressed causing the float to rise and reduce the gas to the by-pass supply for a brief time. In case this temporary restriction of the gas to the burner *p* be found troublesome a push piece or finger *k*, Figs. 2 and 3, is placed on the boiler lid. By means of this when the lid is open and thrown back the float is held down, compression increased and the air underneath the float quickly or almost instantaneously liberated.

If found necessary a small spring valve *h'* may be brought into use as shown by Fig. 5, the push piece or finger *h²* being arranged to press the valve from its seating and thereby pass the imprisoned air to atmosphere.

In the case of pans or boiling vessels used on gas stoves or gas rings, the attachment to the gas regulating valve may differ somewhat to that for the ordinary wash boiler for clothes. For instance, it may be found convenient to use a vertical spindle or rod *f* resting at its lower end on the top of the bell or float *d, e*, Fig. 4, and the other attached to a diaphragm or other type of gas valve with a suitable swivel joint *m* at some point of the spindle or rod for moving the rod out of the way in order (see dotted lines) to lift the float or bell to examine the contents of the pan from time to time. In this case the float being small it can easily be lifted out of the vessel *a* but for ready

access to the contents of the pan *a* I may provide a lip or small door as *d'* hinged to the top of the float as in Fig. 1 and be held in position by a spring.

55

What I do claim as my invention and desire to secure by Letters Patent is:—

1. The combination with a boiling receptacle and heating means therefor having a valve means, of a chamber formed as a part of the receptacle, a float movably mounted in said chamber and moved immediately the liquid in the receptacle gives off a steam vapor in sufficient volume to counteract the cool influence of the exposed surface of the float, and means in part loosely resting upon and engaging the valve means of the heating means and operated by the upper portion of the float and exterior of the receptacle for controlling said heating means proportionately to the movement of the float.

2. The combination with a boiling receptacle and heating means therefor, of a chamber formed as a portion of the receptacle, a float movably mounted in said chamber and inclosed within the chamber to avoid contact with the contents of the receptacle, the said float having a movable cover exposed exteriorly of the chamber, and means controlled by the movement of the cover to engage a portion of the heating means for regulating the degree of heat or the supply of the heating medium to the receptacle.

3. The combination with a boiling receptacle, of a float movably disposed in the receptacle and separated from the containing portion of the latter to avoid contact with the contents of the receptacle, the float being provided with a movable cover, heating means for the receptacle, and a device connected to a portion of the heating means for controlling the supply of heating medium to the receptacle and loosely engaging the said cover.

In testimony whereof I have hereunto set my hand in presence of two subscribing witnesses.

LEE SCHOFIELD.
